Joseph M. Mitchell, 72 High St., Clinton, Mass.

Filed Mar. 16, 1960, Ser. No. 59,764

Term of patent 14 years

(Cl. D9—2)

FIG.1

FIG. 1 is a front elevational view of a combined toothbrush and dental floss holder showing my new design; FIG. 2 is a side elevational view thereof; and FIG. 3 is an end elevation thereof.

The bottom of the combined toothbrush and dental floss holder is substantially plain.

The characteristic feature of my design for a combined toothbrush and dental floss holder resides in the floss housing having the configuration shown.

I claim:

The ornamental design for a combined toothbrush and dental floss holder, as shown.
